UNITED STATES PATENT OFFICE

FREDERICK JOHN DREYSDALE, OF MIDDLE BRIGHTON, AUSTRALIA

SUN BLIND

Application filed July 23, 1930, Serial No. 489,751, and in Australia August 7, 1929.

This invention refers to sun blinds and the like of the kind consisting of a series of slats which are raised or lowered by suitable means such as cords passing around pulleys.

5 In connection with such sun blinds there are two disabilities, one of which is that light through the window is considerably decreased and ventilation impaired and the other is that such blinds cause annoyance by rattling.

One object of the invention is to effect an improvement in the construction of the slats whereby when the blind is drawn down increased light will be obtained without impairing ventilation. Another object is to prevent the slats rattling when the blind is in use.

The invention is illustrated by the accompanying drawings whereof—

20 Fig. 1 is a vertical section through the sun blind when in use and taken on line I—I of Fig. 2.

Fig. 2 is an enlarged horizontal section through the side frame of the blind and—

25 Fig. 3 an enlarged elevation of portion of two slats with a part in section.

Fig. 4 an enlarged detail of the stopping and anti-rattling device and—

Fig. 5 is a detail illustrating a slight modification in the shape of the slat.

As illustrated in these drawings a vertical frame F is fixed at each side of the window opening 1 and preferably cased in metal 2 as shown in Fig. 2.

35 In the face of each frame parallel vertical grooves 3 are formed and the partitions 4 between same are cased in metal, thereby providing smooth linings 5 to the walls of the grooves.

40 A groove 3 is provided for each slat 6 of the blind and it is unnecessary for the linings 5 and also the grooves to extend any further downwardly from the top than the maximum length of movement of the slat in a particular groove. The upper end of each slat 6 is inclined in an upward and inward direction to form deflectors 7 and only the side edges 8 of the vertical portion of the slats engage the grooves 3 in the side frames F.

45 An outwardly projecting bent flange 9 is

formed on the bottom of each slat and a similar but inwardly projecting flange is provided on the upper edge of the upper inclined deflector of the slat.

If desired the side edges 8 of the slats may be bent as at 10 out of vertical plane as the main vertical portion of the slat as illustrated in Fig. 5 in order to strengthen said edges or for the same purpose the edges may be stiffened by metal strips either straight or bent.

The slats when lowered each in turn commencing from the upper one come to rest on individual stops and according to this invention a cam or wedge or bevelled ended block 11 is fixed to the side of each slat near its side edges or the metal strips thereon which blocks, when a slat is lowered contacts with freely rotatable rollers 12 on plates 14 fixed to the side frames F whereby the rollers constitute stops and each slat is supported in its desired position.

The lower or cam faces 13 of the blocks wedge at the back of the rollers and press the slats against one side of the guides in the side frames so that the slat is held firmly in position and rattling of the blind prevented.

Upon the slats being lifted the cam or wedge-shaped blocks are immediately freed from the rollers.

According to the means illustrated for raising and lowering the sun blind, cords 15 attached to the bottom slat at each side pass over suitable pulleys 16 provided above the blind and a common operating cord 17 is guided around a pulley 18 to winding mechanism 19 operated by a crank handle 20.

By means of this gear the nested slats may be supported when the blind is raised and the blind partially or completely lowered, each slat in turn commencing from the outer or upper one coming to rest on its stops. On raising the blind the lowermost one supported on its stops upon moving upwardly engages and correspondingly lifts the slat above and so on till all the slats are nested above the window opening.

On account of the inclined deflector 7 of each slat and the fact that the bend between said inclined end and the vertical portion of

the slat is at a distance from the lower end of the slat above same, which is determined by the positions of the stops, there is a substantial inlet L for sunlight the rays of which on striking the deflector 7 are deflected thereby and so supply substantial illumination for the room. It will be noted however, that the deflectors 7 cover the inlets L and prevent beams of direct sunlight entering the room. Thus the room is shielded from direct sunlight and at the same time ample reflected light floods the room.

In order to enable the slats to be fitted in the grooves 3 of the frames F or be removed therefrom, the grooves in one of such frames terminate a distance from the upper end of such frame equal to the height of a slat, such construction being illustrated in Fig. 1.

20 I claim:—

- 20 1. In sun blinds having independent slats, side frames with separate guides for the slats and separate stops on said frames for each slat, said slats being approximately vertical and formed at the upper end with a deflector inclined in an inward and upward direction, and means to raise and lower said blind.
- 25 2. In sun blinds having independent slats, side frames with separate guides for the slats and separate stops on said frames for each slat, said slats being approximately vertical and formed at the upper end with a deflector inclined in an inward and upward direction, and said stops so located that an inlet is provided between the junction of the vertical portions of the slats with said inclined deflector and the bottom of the adjacent upper slat and said deflectors cover the said inlets against direct entry of light into the room and means to raise and lower said blind.
- 30 3. In sun blinds having independent slats, side frames with separate guides for the slats and separate stops on said frames for each slat, said slats being approximately vertical and formed at the upper end with a deflector inclined in an inward and upward direction, and said stops consisting of rollers which are engaged by cam or wedge shaped blocks fixed on and adjacent the side edges of the slats and means to raise and lower said blind.
- 35 4. In sun blinds having independent slats, side frames with separate guides for the slats and separate stops on said frames for each slat, said slats being approximately vertical and formed at the upper end with a deflector inclined in an inward and upward direction, cords attached to the lowermost slat passed round pulleys above the blind and winding mechanism for operating said cords.

60 FREDERICK JOHN DRYSDALE.
